UNITED STATES PATENT OFFICE.

WALTER M. McLEAN, OF PITTSBURG, PENNSYLVANIA, ASSIGNOR TO W. B. McLEAN MANUFACTURING COMPANY, OF PITTSBURG, PENNSYLVANIA, A CORPORATION OF PENNSYLVANIA.

DESIGN FOR A SHOW-CASE.

No. 40,166.

Specification for Design.

Patented July 20, 1909.

Application filed April 17, 1909. Serial No. 490,649. Term of patent 14 years.

To all whom it may concern:

Be it known that I, WALTER M. McLEAN, a citizen of the United States of America, residing at Pittsburg, county of Allegheny, State of Pennsylvania, have invented a new, original, and ornamental Design for Show-Cases, of which the following is a specification, reference being had to the accompanying drawing, forming part thereof.

The figure is a perspective view of a show case showing my new design.

I claim:

The ornamental design for a show case as shown.

WALTER M. McLEAN.
